UNITED STATES PATENT OFFICE.

HANS BAUMEISTER, OF FRIEDRICHSHAFEN, GERMANY, ASSIGNOR TO ZEPPELIN-WERKE STAAKEN, GESELLSCHAFT MIT BESCHRÄNKTER HAFTUNG, OF STAAKEN-SPANDAU, GERMANY.

FLYING MACHINE.

Application filed March 2, 1921. Serial No. 449,271.

To all whom it may concern:

Be it known that I, HANS BAUMEISTER, a citizen of Germany, residing at Friedrichshafen, Germany, have invented certain new 5 and useful Improvements in Flying Machines (for which I have filed an application in Germany June 12, 1919), of which the following is a specification.

My invention relates to flying machines 10 and aims at simplifying the construction of the same. More in particular, my invention tends to obviate for the future the use of special structures such as have been hitherto required as connecting members even in 15 cases where the supporting plane was separated from the car housing the engines, or from the engine bed, by but a short distance.

It has already been proposed for this purpose to entirely enclose the motor plant in 20 the supporting planes of the flying machine. However, in so doing, the construction of the supporting plane is considerably impaired while, on the other hand, the arrangement of the motor installation, and, above all, the 25 carrying out of any repair work, such as may be required to be done from time to time, or the exchanging of parts, etc., at the motors, is seriously hindered.

Now, my improved construction renders it 30 only to the least possible degree necessary to effect any change in the structure of the framework sections of the supporting plane, while at the same time, by its very means, every desired possibility is afforded of fitting in the motor, not only in the plane of the supporting surface, but likewise also on the outside, or in front of or to the rear of the supporting surface, and this by the provision of special girders adapted to carry or 35 accommodate the motors, said girders being essentially disposed in the longitudinal direction of the flying machine, and connected from without to the supporting plane. In a construction of this kind the setting up and 40 removing of the motor may be effected all the more easily as the bed or foundation of the motor will likewise not be contained within the interior of the supporting plane. At the same time it is immaterial whether the 45 girders serving as a foundation for the motor, are connected to the frame of the supporting plane either above the upper surface or below the underside of said supporting plane, and whether the engine casing enclos-

ing the motors extend downward or upward 55 from the girders. Notwithstanding, the entire construction will be essentially simplified by the girders being arranged at the underside of the supporting surface, and their ends projecting beyond either the 60 front, the rear, or even beyond both edges of the supporting surface, and by only the projecting ends of the girders being used as a foundation for the motors, or the engine casing. Although, in view of the greater accessibility obtained thereby, it will be most 65 expedient to arrange the motors at either the forward or rearward edge of the supporting surface, the engine casings may, owing to the provision of the girders, be to a greater 70 or less extent built into the supporting surface area, even as the conditions prevailing for the time being may render advisable, by merely providing suitable openings at the proper points within the supporting surfaces. 75

Two forms of a flying machine embodying my invention are shown by way of example in the accompanying drawings, in which,

Fig. 1 is a side elevation partly in section 80 on line 1—1 in Fig. 3, of the supporting surface of a flying machine having a triple motor installation,

Fig. 2 the front view appertaining thereto, 85 Fig. 3 a corresponding plan view.

Fig. 4 a part-sectional view on line 4—4 in Fig. 5, and

Fig. 5 a plan view of the supporting surface of a flying machine having two motor installations. 90

In the construction according to Figs. 1 to 3, there are connected to the underside of a supporting surface A a centrally disposed pair of girders B and two pairs of outside girders B¹. All these six girders are lattice 95 girders. The several pairs of girders are staggered relatively to each other from the front toward the rear, in such wise that the outside pairs B¹ will project for a considerable distance beyond the front edge of the 100 supporting surface, while the inside pair B terminates in a line with the rear edge of the supporting surface. The outer ends of each pair serve as a base or foundation for the three motor installations C and C¹, respectively; the center motor operating a pressure propeller, and each of the two outer motors a pulling propeller. As shown in 105

the drawing, the outer motor installations C¹ are arranged for the main part in front of the supporting plane, while the central motor installation C projects for its full 5 length into the rear portion thereof.

In the form of construction disclosed by Figs. 4 and 5, there are connected to the underside of a supporting surface D two plate girders E, which while almost terminating in a line with the rear edge of the 10 supporting plane, project for about one-half of their length beyond the front edge thereof. The free ends of each pair of girders constitute each the bed or foundation 15 for a forward and a rearward motor installation, respectively. The forward installation F projects in the horizontal section, for about one-half its length into the supporting plane D, the rearward installation F¹ almost entirely into the said supporting plane. The opening made at the rear edge of the supporting plane D is consequently substantially deeper, than the one at the front edge. The motor installations, 20 together with the bed or foundation carrying them, are provided in a well known manner with a casing adapted to minimize the air resistance.

In the form of execution shown, it is 30 assumed that the girders carrying the motors are merely fixed to the underside of the supporting plane, because a construction of this type will be most frequently employed in practice. However, even in 35 such a case it may at times prove expedient

to connect the girders in addition with the one or the other section of the upper surface of the supporting plane. On the other hand, for example, a girder running right through the supporting plane itself might 40 be arranged to support either upon a forward or rearward extension or projection a motor lodged in its entirety somewhat above the supporting plane.

I claim:

1. In a flying machine in combination, a supporting surface, a girder externally attached to said surface and extending substantially longitudinally of said flying machine, and a motor carried by said girder. 45

2. In a flying machine in combination, a supporting surface, a pair of girders externally attached to said surface and extending substantially longitudinally of said flying machine, and a motor carried by said 55 girders.

3. In a flying machine in combination, a supporting surface, girders attached to the bottom face of said supporting surface and projecting at least beyond one edge thereof, 60 and a motor carried by said girders.

4. In a flying machine in combination, a supporting surface, a plurality of girders attached to the bottom face of said supporting surface and projecting beyond opposite 65 edges thereof, and a motor on the projecting ends of said girders.

In testimony whereof I affix my signature.

HANS BAUMEISTER.
